SHEET GLASS APPARATUS

Filed Sept. 23, 1926

FIG. 1

FIG. 2

Attorney

UNITED STATES PATENT OFFICE

LUKE C. MAMBOURG, OF LANCASTER, OHIO, ASSIGNOR TO THE LIBBEY-OWENS GLASS COMPANY, OF TOLEDO, OHIO, A CORPORATION OF OHIO

SHEET-GLASS APPARATUS

Application filed September 23, 1926. Serial No. 137,180.

This invention is an improvement in the art of drawing sheet glass, and relates more particularly to improved apparatus for maintaining the width of the sheet.

While this invention is not limited to use with any one system of producing sheet glass, it is illustrated in connection with an apparatus of the general type set forth in the patent to Colburn, No. 1,248,809, granted December 4, 1917. In this system a continuous sheet of glass is drawn upwardly from a bath of molten glass, and then while in a semi-plastic condition, although substantially set in its final sheet form, is bent into a horizontal plane and carried off through a suitable drawing mechanism and into a leer. As is well known in the art, some means must be provided to maintain the width of the sheet drawn, otherwise it will gradually narrow away until no sheet is left. The prior art structures make use of so-called knurled rollers which are usually positioned in the meniscus at its opposite ends, by which the sheet is prevented from narrowing according to its natural tendency. It has been customary prior to the present invention to arrange these knurled rollers horizontally and so that they engage the sheet at substantially right angles relative thereto.

An important object of the present invention is the provision of means which will not only serve to maintain the sheet to width, but will act to stretch the sheet or produce a sheet relatively wider than its base, thus making it possible to produce a sheet of greater width than with the old arrangement.

Another object of the invention is the provision of width maintaining and sheet stretching means in the form of rotatable members engaging the edges of the sheet, and preferably arranged at an angle other than a right angle relative to said sheet.

Another object of the invention is the provision of knurled rollers extending diagonally of the sheet for maintaining the same to width, and for exerting a lateral tension thereto.

A further object of the invention is the provision of means for raising and lowering the knurled rollers, together with means for ad-

justing the angle of the said rollers relative to the sheet.

Other objects and advantages of the invention will become more apparent during the course of the following description when taken in connection with the accompanying drawings.

In the drawings wherein like numerals are employed to designate like parts throughout the same,

Fig. 1 is a longitudinal vertical section through a sheet drawing apparatus showing associated therewith width maintaining means constructed in accordance with the present invention.

Fig. 2 is a view taken at right angles to Fig. 1, and

Fig. 3 is a plan view taken on line 3—3 of Fig. 2.

Referring to the drawings, the numeral 10 designates a draw pot in which is disposed a bath of molten glass 11. The pot 10 rests upon suitable supports and is heated from the bottom by means of burners or the like, which apparatus is not shown in the drawings. The sheet 12 is drawn from the pot 10, and is trained over a bending roll 13, then over the draw table and leer until the sheet has been satisfactorily completed. In the absence of suitable width maintainers, the sheet does not keep a desired width, so to prevent this narrowing up, rollers 14 are placed on both sides of the glass and at opposite edges thereof, and preferably in the meniscus 15.

The knurled rollers 14 are carried upon tubes or hollow shafts 16 journaled in suitable bearings 17 mounted upon a base 18. Gears 19 are keyed on the tubes 16 and in constant mesh with each other as shown in Fig. 3. One way of mounting the tubes is to have one tube fixed and the other mounted upon a pivot or the like so that the pivoted tube can be moved to and from the stationary tube. A spring 20 is arranged between the outer ends of the tubes, to normally urge the knurled rollers toward each other. Of course, the spring will be sufficiently weak or resilient to permit the drawing of glass between the knurled rollers. A beveled gear 21 is carried by one of the tubes while a drive pinion 22 is

in mesh therewith to rotate both of the tubes simultaneously and in opposite directions.

In order to keep the knurled rollers 14 from overheating, pipes 23 are run through the tubes in such a manner that a continuous flow of cooling medium can be passed through the rollers so that an even and constant temperature can be maintained.

It is to be noted that the knurled rollers 14 extend diagonally of the sheet, or at an obtuse angle relative thereto. By being so positioned, the knurled rollers 14 will serve not only to maintain the sheet to width, but will also act to stretch the sheet transversely, thus making it possible to obtain a wider sheet than has heretofore been possible from a given width of pot.

In the Colburn machine above referred to, wherein the knurled rollers are arranged horizontally and at right angles to the sheet, it is customary to blow a jet of air on the edges of the sheet to assist in building up the edges and maintaining the sheet to width. This process results in the formation of a relatively thick edge portion which extends inwardly on the sheet a substantial distance. However, by tilting the knurled rollers relative to the sheet as taught by the present invention, it is possible to eliminate the necessity of blowing a jet of air on the edges of the sheet. Moreover, when the rollers are so tilted relative to the sheet they will serve to grip and direct the edges thereof upwardly and outwardly, thereby stretching the sheet transversely whereby to permit a relatively wider sheet to be drawn from a given width of pot than with the old arrangement.

The base 18 is pivotally mounted as at 24 to a bearing member 25 which is provided with a depending screw-threaded rod 26, which is received within a supporting frame 27. A nut 28 is threaded on the rod 26, and rests upon the frame 27. Thus, the base 18 and knurled rollers 14 can be readily raised and lowered relative to the draw pot 10 by simply rotating the nut 28 in the desired direction.

Carried by the bearing member 25 are outwardly and oppositely directed lugs 29 through which are threaded vertical adjusting screws 30 which contact with the bottom of the base 18. When it is desired to adjust the angle of the knurled rollers 14 relative to the sheet 12, it is simply necessary to loosen one of the adjusting screws 30 and subsequently tighten the other screw, whereupon the base 18 will be rocked about its pivot 24 to change the angle of the rollers 14.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

Claims:

1. In sheet glass apparatus, a receptacle adapted to contain a mass of molten glass, means for drawing a sheet therefrom, rollers engaging both sides of the sheet at the opposite edges thereof, said rollers being inclined at an angle to the direction of movement of the sheet being drawn, shafts carrying said rollers, a base for supporting said shafts, a bearing member to which the base is pivotally mounted, oppositely directed lugs carried by said bearing member, and adjusting screws passing upwardly through the lugs and bearing against the undersurface of said base. 70

2. In sheet glass apparatus, a receptacle adapted to contain a mass of molten glass, means for drawing a sheet therefrom, rollers engaging both sides of the sheet at the opposite edges thereof, said rollers being inclined at an angle to the direction of movement of the sheet being drawn, shafts carrying said rollers, a base upon which said shafts are mounted, a supporting member for the base having a threaded portion, a supporting frame for receiving the threaded portion therein, and a nut received upon the threaded portion and resting upon said supporting frame. 85

3. In sheet glass apparatus, a receptacle adapted to contain a mass of molten glass, means for drawing a sheet therefrom, rollers engaging both sides of the sheet at the opposite edges thereof, said rollers being inclined at an angle to the direction of movement of the sheet being drawn, shafts carrying said rollers, a base for supporting said shafts, a bearing member to which the base is pivotally mounted, said bearing member being provided with a threaded portion, a supporting frame for receiving the threaded portion therein, a nut received upon the threaded portion and resting upon the supporting frame, oppositely directed lugs carried by said bearing member and adjusting screws passing upwardly through said lugs and bearing against the undersurface of said base. 95 100 105 110

Signed at Lancaster, in the county of Fairfield and State of Ohio, this 16th day of September, 1926.
